CLAIM

We claim the ornamental design for a mounting strip with
spring assembly, as shown and described.

DESCRIPTION

FIG. 1 is a front perspective view from above of a mounting
strip with spring assembly of the spring being shown in a
compressed, biased position;

FIG. 2 is a top perspective view of the claimed design of
FIG. 1;

FIG. 3 is a perspective view from below of the claimed
design of FIG. 1;

FIG. 4 is a right side view of the claimed design of FIG. 1;

FIG. 5 is a left side view of the claimed design of FIG. 1;

FIG. 6 is a top view of the claimed design of FIG. 1;

FIG. 7 is a bottom view of the claimed design of FIG. 1;

FIG. 8 is a front view of the claimed design of FIG. 1; and,

FIG. 9 is an exploded view of the mounting strip with spring
assembly of FIG. 1, the spring being shown in an uncom-
pressed, unbiased position.

The broken lines depict portions of the mounting strip with
spring assembly that form no part of the claimed design. The
dot dash lines in the drawings depict a symbolic break.
The portion between the break lines forms no part of the claimed
design.
